UNITED STATES PATENT OFFICE.

ALBERT J. ELDON, OF MOUNT VERNON, NEW YORK, ASSIGNOR TO THE PARAMOUNT RUBBER CONS., INC., OF TUCKAHOE, NEW YORK, A CORPORATION OF DELAWARE.

DESIGN FOR A SWIMMING RING.

Application filed January 19, 1925. Serial No. 12,087. Term of patent 7 years.

To all whom it may concern:

Be it known that I, ALBERT J. ELDON, a citizen of the United States, residing at Mount Vernon, in the county of Westchester and State of New York, have invented a new, original, and ornamental Design for a Swimming Ring, of which the following is a specification, reference being had to the accompanying drawing, forming a part thereof.

In the drawing, I have shown a perspective view of a swimming ring embodying my invention.

I claim:

The ornamental design for a swimming ring substantially as shown.

ALBERT J. ELDON.
